UNITED STATES PATENT OFFICE

2,418,263

VALVE CONTROLLED ROTARY HOPPER BAG
FILLING MACHINE AND METHOD

George L. Hurst, San Francisco, Calif.

Application December 7, 1943, Serial No. 513,223

10 Claims. (Cl. 226—61)

1

This invention relates to a sacking machine, and has for one of its objects a machine that will function to automatically and uniformly load sacks with flowable material such as rice, grain, and that will automatically deliver sacks so loaded onto a conveyor, platform, or to a conventional sack-sewing machine.

Another object is the provision of improved means in a sacking machine for supplying a uniform amount of material such as rice, grain, etc., to each of the sacks including a simple structure for quickly and accurately varying the amount so supplied.

A still further object of the invention is the provision of an improved sacking machine that may be operated with the minimum of labor and attention for more rapidly filling sacks than heretofore.

Heretofore the filling of rice sacks or grain sacks with rice, grain, or the like, preparatory to their being sewed shut by a conventional sack-sewing machine has been a relatively slow and expensive procedure. According to the usual method, a workman is positioned at each of a number of filling stations where he may manually hold the sack during filling thereof from the discharge conduit, chute, or the like, of a hopper, which conduit is provided with a gate that is manually controlled by the operator. The operator may intermittently jolt the sack to insure a reasonably compact fill of material therein, and after each sack is filled he delivers it onto a conveyor for delivery by the latter to the sewing machine. Each operator may fill about 100 sacks per hour, although there usually is considerable variation in the amount of rice, grain, or the like, in each sack.

With my machine an operator merely fits the mouth of each sack over a holder as the latter moves by the operator and as soon as the sack is so fitted he pulls a lever that is associated with the frame and the sack is locked to the frame substantially simultaneously with the opening of a feed hopper for discharge of its contents into the sack. The sack is automatically jolted and filled with a measured quantity of rice, grain, or the like, and at a predetermined point in its travel the feed hopper is closed about simultaneously with a release of the filled sack onto a conveyor that carries it away in upright position to a sewing machine. With this machine a single relatively inexperienced operator may fill upwards of 600 sacks per hour, and the sacks so filled each contain a substantially uniform amount of material.

2

Other objects and advantages will appear in the description and drawings annexed hereto.

In the drawings:

Fig. 1 is a plan view of a sacking machine illustrative of my invention. A sewing machine is diagrammatically indicated in this view and other features therein are semi-diagrammatically illustrated.

Fig. 2 is an enlarged part sectional, part plan view of one of the sack holding frames and feed gates indicated in plan view in Fig. 1.

Fig. 3 is a side elevational view of the structure and elements shown in Fig. 2.

Fig. 4 is a part sectional, part end elevational view of the structure shown in Fig. 3.

Fig. 5 is a semi-diagrammatic, simplified side elevational view of the sacking machine of Fig. 1 as seen from the side thereof from which a filled sack is discharged. Only one of the sack-holding frames and elements associated is illustrated complete so as to avoid confusion in the drawing.

Fig. 6 is an enlarged fragmentary elevational view of the variable control means for controlling the amount of rice, grain, etc., that is to be discharged into each sack.

In detail, the sacking machine illustrated in the drawings comprises a garner bin 1 or any other source of supply for any flowable material such as rice, grain, etc. A downwardly extending spout 2 from bin 1 has its discharge end directed downwardly into a revolving, vertically disposed, cylindrical drum 3 that is supported on a central vertical shaft 4 for revolving about the axis of the latter.

The bottom 5 of drum 3 is conical with its apex uppermost and concentric with said shaft 4, the latter extending through said bottom at said apex to a bearing on a top cross frame member 6 of a rectangular top frame 7. Vertical legs 8 (Fig. 5) are provided for said top frame and a bearing 9 supports the lower end of shaft 4 on the floor or below bottom 5.

The interior of drum 3 is divided into a plurality of identical hoppers 10 (Fig. 1) by similar, 45 equally spaced, vertical partitions 11 extending radially of the drum axis and from shaft 4 to the cylindrical drum walls and to bottom 5. The drum 3 provides the outer wall for each hopper 10 and the bottom 5 provides the bottom wall.

The discharge end of spout 2 is offset to one side of the shaft 4 about midway between the shaft 4 and drum 3 and is directed downwardly with its free edges in a horizontal plane. Partitions 11 extend upwardly to a point about level 55 with the upper edges of the drum 3, and the

spout clears the partitions so that the drum may revolve while material flows into the hoppers as they successively pass beneath the spout.

The walls 5 of each hopper 10 (which wall is part of drum 3) is provided with an opening 12 (Fig. 4) centrally between each adjacent pair of partitions 11, which opening extends upwardly from adjacent the lower edge of bottom 5, and the slant of bottom 5 is such that each hopper will be cleared of its contents by flow of said contents by gravity through each opening when each of the latter is opened.

In Fig. 1 six partitions 11 are shown, thus dividing the drum into 6 hoppers, but it is obvious that any desired number more or less than six may be provided. In Fig. 2 a plan and part sectional view of the structure adjacent each opening in wall 5 is disclosed. It is understood that each of the six similarly appearing structures in Fig. 1 is identical with that shown in Fig. 2, and in Figs. 3 and 4, the latter being a side and end view of the structure of Fig. 2.

A vertically slideable gate or closure 13 is provided for closing and opening each of the openings 12, such gate being supported at its two opposite lateral edges in grooves or guideways adjacent the two opposite lateral edges of opening 12 for sliding downwardly from an open position to closed position and vice versa.

Secured to each gate 13 (Fig. 4) adjacent its upper edge and centrally between its side edges is a plate 14 that is adapted to engage a stop member 15 on wall 3 when the gate 13 is in elevated open position fully uncovering the opening 12. This plate 14 carries a shaft 16 projecting outwardly therefrom relative to the drum and radially of the drum axis. The shaft 16 supports a roller 17 rotatable thereon adjacent plate 14, and a pair of toggle links 18, 19 (Fig. 3) are connected at their adjacent ends to the outer end of said shaft. Links 18, 19 extend substantially horizontally from shaft 16 when gate 13 is in elevated open position, and they are pivotally secured at their outer ends by pivots 20 to the upper ends of a pair of generally vertically extending arms 21. The arms 21 are pivotally supported intermediate their ends by pivots 21' to the sides of yoke members 22, the said arms being between each pair of said members as seen in Fig. 2.

The members 22 are secured to two opposed side walls 24 extending at right angles to a deflector plate or shield 23. These sides are formed with flanges 25 along one of their edges for securing to drum 3 along two opposite lateral edges of each opening 12, and said sides support the main deflector plate 23 in spaced relation to said drum outwardly of said opening and in a position extending over the same. Thus the contents of each hopper 10 will be deflected downwardly by plate 23 when such contents is discharged through opening 12, and the sides 24 will function to prevent spilling of such contents laterally.

The toggle link 19 of each pair is provided with an extension 26 that extends slantingly downwardly relative to horizontal when said links are about horizontal and the gate 13 is open, as seen in Fig. 3.

The lower part of each arm 21 that projects below each pivot 21' preferably extends angularly outwardly in an inclined direction away from the side 24 that is adjacent thereto (Fig. 3), and the outer end of each such lower part carries a flat leaf spring 27 that projects vertically downwardly therefrom. The lower end of each spring 27

carries a generally U-shaped clamping element 28 and each such element is adapted to engage one of the two opposite ends of a centrally open horizontally elongated frame 29. Each frame 29 may be formed from a strip of metal and along the lower edge of each frame is formed an outwardly projecting bead or ridge 30 that extends just below the clamping members 28.

Each frame 29 is adapted to fit within the upper open end of a conventional fabric sack, such as a rice or grain sack, and when the clamping elements 28 are swung to yieldably grip the sack between the ends of frame 29 and said elements at points above said ridge 30, the sack will support a full load from one of hoppers 10 therein without slipping from the frame 29 (Fig. 3).

In operation the drum 3 is rotated by means of a motor 31 that is connected with the drum by suitable gears and chains or belts and the like, generally indicated at 32 (Fig. 1). The arrow in Fig. 1 indicates the direction of rotation of said drum. At point or station A the clamping members 28 are in the dotted line position indicated at 33 in Fig. 3 and the gate 13 is closed. Handle 26, roller 17, and toggle links 18, 19 are also in the dotted line position shown in Fig. 3.

Station A is the point where an operator slips the mouth of a sack 34 (indicated in dot-dash line in Fig. 3) over frame 29 while the latter moves past him, and also pulls down lever 26 from its dotted position 35 (Fig. 3) to its full line position; thus clamping the sack to the frame and opening gate 13 at the same time. The springs 27 are under some tension when the clamping elements 28 are in sack clamping position and pivot 16 may move upwardly just past dead center in which links 18, 19 are in horizontal alignment, thus securely holding said elements 28 in clamping position until positively released by a force moving the adjacent ends of the toggle links downwardly. Also gate 13 is held open until such downward movement. The ridge 30 on frame 29 functions somewhat as a snubber to prevent slippage of the sack on frame 29 when the latter is being filled and vibrated.

Immediately upon opening the gate 13 the material in the hopper 10 that carries said gate and said sack will commence flowing into the sack. It is pertinent to note that said hopper at this time has passed beyond the discharge end of spout 2.

As the sack is carried by the turret drum 3 in the direction of the arrow (Fig. 1) it slidably engages a vibrator 36 that may engage a side and bottom of the sack. This vibrator is in the form of a curved plate that is connected by a link 37 with an eccentric or crank secured on a shaft 38, the latter being revolved by any suitable source of power, such as a motor 39 (Figs. 1, 5). Thus the sack is vibrated during part of its travel after gate 13 has been opened and the contents of hopper 10 carrying said sack has partially or fully been discharged into such sack.

After the sack is carried past the vibrator 36 the roller or wheel 17 engages a generally U-shaped cam-track 40 (Fig. 5) that may be rigidly secured to posts 41 that in turn are depending from an upper cross-frame member 42. The latter is shown partially broken away in Fig. 1.

As the roller passes under cam-track 40 in engagement with the latter, it is forced downwardly, thus moving gate 13 to closed position and swinging the clamps away from the sack whereupon the latter is dropped onto conveyor 45 for movement away from the sacking machine and

past a conventional sack-sewing machine 46 that sews the mouth of the sack closed. Spaced guide bars 47 above conveyor 45 support the filled sack on the latter against toppling over. The filled sack is indicated in dot-dash line 34 in Fig. 5.

The closing of gate 13 and the dropping of filled sack 34 from frame 29 occurs substantially simultaneously and just before the hopper 10, that has carried said sack, moves to below the discharge end of spout 2.

The spout 2 includes at its outer end a tubular extension 50 that is telescopically fitted on the main spout for axial movement relative to the latter. This extension 50 carries the discharge end for material passing through spout 2 and the edges of the extension defining the discharge opening are in a common horizontal plane (Fig. 6).

In operation, said spout 2 and extension 50 are preferably open at all times during operation of the sacking machine. Assuming rice is being sacked, such rice flows into the hopper 10 almost immediately after gate 13 has been closed due to the engagement between the roller 17 and cam track 40. Before said hopper 10 moves from under the discharge end of extension 50 as indicated by dot-dash lines 51 (Fig. 6) so that the edges of the body of rice in each hopper 10 that passes said extension will be considerably below the upper edges of each partition 11 and drum 3 when the extension is adjusted so that its discharge end just clears said partitions.

Extension 50 carries a rack 52, the teeth of which are in mesh with those of a gear 53. Gear 53 may be secured on a rotatable shaft 54 that in turn carries a gear 55 in mesh with a worm 56, the latter being secured to a rotatable shaft 57 having a wheel 58 for manually rotating the same (Figs. 1, 5). By rotating shaft 57 in one direction the operator may cause the extension 50 to be retracted on spout 2 until its discharge end may be at the level indicated by dot-dash line 60 (Fig. 6) in which position the slope of the rice in hopper 10 will be coincident with dot-dash line 61, and an appreciably greater quantity of rice will be in the hopper than when the extension was in its lowered position. The extension 50 will automatically remain in any adjusted position due to the gear-worm connection 55, 56, and an extremely accurate control of the amount of rice, grain, or any other similarly flowable material that is to be discharged into the sacks may be obtained. This is quite an important feature of the invention inasmuch as one of the most desired results in sacking material such as rice and grain is to obtain a uniform amount of such material in each sack. The adjustment provides convenient and accurate means for controlling the contents of each hopper beyond a certain minimum volume both as to volume and weight.

It is to be understood that the drawings are illustrative and not restrictive of the invention since it is obvious that certain structure can be modified or changed without changing the invention.

Having described my invention, I claim:

1. The method of filling sacks with rice and the like that comprises the steps of; continuously moving a plurality of feed hoppers along a common path of travel, successively filling said hoppers to a predetermined level at a point in said path, suspending a sack vertical with its mouth open adjacent each of said hoppers for movement therewith as each hopper is filled, then discharg-

ing the contents of each such hopper into the sack during movement of the hoppers in said path, and thereafter releasing each sack for movement thereof away from said common path and so moving each released sack.

2. The method of filling sacks with rice and the like that comprises the steps of; continuously moving a plurality of feed hoppers along an annular path of travel, successively filling said hoppers to a predetermined level at a point in said path, then suspending a sack vertical from each hopper so filled for movement therewith and simultaneously with such suspension opening the hopper for discharge of its contents into the sack suspended therefrom, thereafter closing each hopper and simultaneously therewith releasing the sack suspended therefrom before each hopper reaches said point.

3. A sacking machine of the character described comprising a plurality of feed hoppers arranged in a row, means supporting said hoppers for movement in a circular path, means for simultaneously so moving said hoppers, a discharge opening formed in the lower portion of each hopper for discharging material therefrom, a movable closure for each of said openings, a support for a sack adjacent each opening secured to each hopper for movement therewith, means for filling each hopper to a predetermined level, means for moving said closures from over said openings to permit discharge of the contents of each hopper into the sack adjacent each of said openings, means for automatically moving each closure to a position closing each opening after the contents of each hopper has been discharged into the sack adjacent thereto and during said movement of said hoppers.

4. A sacking machine of the character described comprising a plurality of feed hoppers arranged in a row, means supporting said hoppers for movement in a circular path, means for simultaneously so moving said hoppers, a discharge opening formed in the lower portion of each hopper for discharging material therefrom, a movable closure for each of said openings, a support for a sack adjacent each opening secured to each hopper for movement therewith, means for filling each hopper to a predetermined level, means for moving said closures from over said openings to permit discharge of the contents of each hopper into the sack adjacent each of said openings, means for automatically moving each closure to a position closing each opening after the contents of each hopper has been discharged into the sack adjacent thereto and during said movement of said hoppers, each of said supports including a vertically open frame secured to each hopper adapted to fit within the mouth of each sack and members releasably securing the mouth of each sack to each of said frames.

5. A sacking machine of the character described comprising a plurality of feed hoppers arranged in a row, means supporting said hoppers for movement in a circular path, means for simultaneously so moving said hoppers, a discharge opening formed in the lower portion of each hopper for discharging material therefrom, a movable closure for each of said openings, a support for a sack adjacent each opening secured to each hopper for movement therewith, means for filling each hopper to a predetermined level, means for moving said closures from over said openings to permit discharge of the contents of each hopper into the sack adjacent each

of said opening, means for automatically moving each closure to a position closing each opening after the contents of each hopper has been discharged into the sack adjacent thereto and during said movement of said hoppers, the said means for filling each hopper comprising a source of supply of material for said hoppers, a spout in the form of a tube extending from said source to a point over the said hoppers when they are moved longitudinally of said row, the upper sides of said hoppers being open for receiving such material from said tube as the hoppers are so moved past said tube.

6. A sacking machine of the character described comprising a plurality of feed hoppers arranged in a row, means supporting said hoppers for movement in a circular path, means for simultaneously so moving said hoppers, a discharge opening formed in the lower portion of each hopper for discharging material therefrom, a movable closure for each of said openings, a support for a sack adjacent each opening secured to each hopper for movement therewith, means for filling each hopper to a predetermined level, means for moving said closures from over said openings to permit discharge of the contents of each hopper into the sack adjacent each of said openings, means for automatically moving each closure to a position closing each opening after the contents of each hopper has been discharged into the sack adjacent thereto and during said movement of said hoppers, the side walls of said hoppers being sections of a single vertically disposed drum provided with radially extending partitions therein separating adjacent hoppers, and the bottom walls of said hoppers being sections of a conical member extending from the lower edges of said drum upwardly toward the central axis of the latter whereby the material in each hopper will slide on the bottom thereof to the section of the drum forming one of the lateral side walls thereof, and each of said openings being formed in each of said latter sections.

7. A sacking machine of the character described comprising; a horizontally disposed annular row of upwardly opening feed hoppers supported for movement in a circular path, a discharge opening formed in the radially outwardly facing side of each of said hoppers, a closure for each of said openings movable from a position closing each of the latter to a position opening the same and vice versa, a source of material for said hoppers including a stationary discharge spout opening downwardly at a point over the said row for discharging such material into the said hoppers as they move past said spout, movable members for releasably securing the mouth end of a sack to each hopper in a position adjacent each of said openings for receiving the contents of each hopper when the said closures are opened, means connecting said members and said closures for simultaneous movement thereof for releasing said sacks and closing said openings respectively, means for moving said hoppers simultaneously in said one direction.

8. A sacking machine of the character described comprising; a horizontally disposed annular row of upwardly opening feed hoppers supported for movement in a circular path, a discharge opening formed in the radially outwardly facing side of each of said hoppers, a closure for each of said openings movable from a position closing each of the latter to a position opening the same and vice versa, a source of material for

said hoppers including a stationary discharge spout opening downwardly at a point over the said row for discharging such material into the said hoppers as they move past said spout, movable members for releasably securing the mouth end of a sack to each hopper in a position adjacent each of said openings for receiving the contents of each hopper when the said closures are opened, means connecting said members and said closures for simultaneous movement thereof for releasing said sacks and closing said openings respectively, means for moving said hoppers simultaneously in said one direction, and means at a fixed point adjacent said row for causing said last mentioned movement of said members and closures as the said members and closures arrive at said point during their movement around said axis with said hoppers, said members and said closures being carried by said hoppers for movement with the latter.

9. A sacking machine of the character described comprising; a horizontally disposed annular row of upwardly opening feed hoppers supported for movement in a circular path, a discharge opening formed in the radially outwardly facing side of each of said hoppers, a closure for each of said openings movable from a position closing each of the latter to a position opening the same and vice versa, a source of material for said hoppers including a stationary discharge spout opening downwardly at a point over the said row for discharging such material into the said hoppers as they move past said spout, movable members for releasably securing the mouth end of a sack to each hopper in a position adjacent each of said openings for receiving the contents of each hopper when the said closures are opened, means connecting said members and said closures for simultaneous movement thereof for releasing said sacks and closing said openings respectively, means for moving said hoppers simultaneously in said one direction, a centrally open frame secured to each hopper adjacent the said discharge opening in the latter arranged and adapted to fit within the mouth of each sack, and means supporting said members for movement from a position adapted to clamp said mouth to said frame at spaced points on the latter to a position releasing said mouth from said frame.

10. A sacking machine of the character described comprising; a horizontally disposed annular row of upwardly opening feed hoppers supported for movement in a circular path, a discharge opening formed in the radially outwardly facing side of each of said hoppers, a closure for each of said openings movable from a position closing each of the latter to a position opening the same and vice versa, a source of material for said hoppers including a stationary discharge spout opening downwardly at a point over the said row for discharging such material into the said hoppers as they move past said spout, movable members for releasably securing the mouth end of a sack to each hopper in a position adjacent each of said openings for receiving the contents of each hopper when the said closures are opened, means connecting said members and said closures for simultaneous movement thereof for releasing said sacks and closing said openings respectively, means for moving said hoppers simultaneously in said one direction, a centrally open frame secured to each hopper adjacent the said discharge opening in the latter arranged and adapted to fit within the mouth of each sack, and means supporting said members for movement from a position

adapted to clamp said mouth to said frame at spaced points on the latter to a position releasing said mouth from said frame, said last mentioned means including springs for yieldably urging said members into clamping relation with said mouth and frame.
